FILTER AND MEANS FOR CONTROLLING THE PULP LEVEL THEREIN

Application filed October 1, 1925. Serial No. 59,759.

This invention relates to automatic feeding and feed control mechanism for continuous filters.

One of the objects of the invention is to provide a mechanism for feeding and automatically controlling the flow of pulp into a continuously operated filter without the use of a power driven pump.

Another object of the invention is to provide for maintaining the pulp in a continuously operated filter at a predetermined level.

Another object of the invention is to provide a feed regulation for continuous filters which will automatically stop the filter and relieve the pressure therein when the pulp in the filter rises above a predetermined level.

Another object of the invention is to provide automatic means for gradually feeding pulp into a continuously operated filter.

Various other objects of the invention will appear as the description proceeds.

In the drawings, which illustrate one form of embodiment of the invention—

Figure 1 is an elevational view of a filter and feeding and feed control mechanism therefor;

Figure 2 is an enlarged view of the pulp level controlling means shown in Fig. 1;

Figure 3 is an enlarged side view of the controlling means shown in Figure 2.

Referring more specifically to the drawings, the continuous filter 10, which may be of either the pressure or suction type, as is well known in the art, comprises a casing 11 inside of which a series of circular filter leaves or a drum is mounted upon the rotating hollow shaft 12 through which the filtrate is drawn off. The pulp or sludge is admitted through a valve 13 to the desired level and the inside of the casing subjected to air pressure, such air being supplied through the pipe 14 to cause flow of the filtrate through the filter surface in the case of a pressure filter or the shaft 12 is subjected to a vacuum in a vacuum filter to draw the filtrate therethrough. As the liquid in the pulp is forced through the filter surface the cake is deposited on the outside thereof and as the filter revolves with the hollow shaft 12, the cake is scraped off the surface and deposited outside the sludge

tank. The level of the pulp in the filter should be kept below the top of the sludge tank so that none of the sludge flows over the sides thereof. To effect this the flow of pulp into the filter is automatically controlled by the valve 13 which is balanced so that its operation will not be affected by a difference in pressure and is operated by a piston in the air cylinder 16. Air is admitted to the cylinder 16 through a pilot valve 17, which is in turn controlled by the float 18 through the lever 19, the shaft 20, the lever 21 and the link 22. The float 18 is raised and lowered by the pulp in the filter and when the pulp rises to a predetermined level the float 18 actuates the pilot valve 17, admitting air into one end of the cylinder 16, which closes the valve 13 so that no more pulp is admitted to the filter. When the level of the pulp lowers, the float 18 is lowered, the pilot valve 17 is actuated thus admitting air into the opposite end of the cylinder 16, and the valve 13 is opened, allowing the pulp to flow into the filter.

An electrical emergency cut-off is provided which operates in case the valve 13 does not close properly and the pulp continues to flow into the filter. A contact arm 23 is attached to the shaft 20 and when the float 18 has moved upwardly a predetermined distance past the normal high level of the pulp, the contact arm 23 presses against the button 24, and an electric circuit is closed through the solenoid 25, which raises the lever 26 and turns the three-way cock 27, thereby shutting off the high pressure air flowing through the pipe 28 and allowing the air in pipes 29 and 30 to the filter and monte-jus 31 respectively to escape through the exhaust port of the cock. This relieves the pressure in the pipe 14 and in the filter casing and also in a manner to be hereinafter described prevents more pulp from being forced into the filter from the monte-jus. If desired, the escaping air may be made to throw a switch and thus shut off the driving power of the filter.

In order to force the pulp into the filter, an apparatus commonly known in the art as a monte-jus is used. This device comprises a tank 31 which communicates through an opening in the bottom and a T-connection 32

with the feed pipe 33 and the filter 10. Swing-check valves 34 and 35 are placed at either side of the connection 32 and are so placed that pulp may pass through them only in the direction of the filter. The compressed air pipe 30 opens into the top of the tank or monte-jus and air flow therethrough is controlled by a three-way cock 36. This cock is operated by the air cylinder 37 which is controlled by a pilot valve 38 similar to valve 17. A float 39 is attached to the shaft 40 extending through the walls of the tank by means of the lever 41, and an arm 42 and link 43 communicate the movement of the float 39 to the pilot valve 38. Hence when the float 39 is caused to move upwardly by the rising of the pulp in the tank 31, the pilot valve 38 is actuated, admitting air into one end of the cylinder 37. The three-way cock 36 is then operated by the piston in the cylinder 37 to stop the escape of the air being exhausted from the tank 31 by the raising of the sludge therein, while at the same time compressed air is admitted to the tank 31 through the three-way cock 36 to put the sludge in the tank under pressure and cause it to flow into the filter when the valve 13 is open.

The operation of the system is as follows:

Pulp is fed by gravity or any suitable means through the feed pipe 33 and check valve 35 into the tank 31 of the monte-jus. As the exhaust port of the cock 36 is opened the air in the tank passes out through the cock and allows the pulp to rise in the tank until it raises the float 39. Raising the float 39 closes the exhaust port of the cock 36 and at the same time allows high pressure air to pass into the tank 31 through the pipe 30. The pulp is forced downwardly by the air and as the check valve 35 closes under the pressure, it can only pass through the check valve 34 and up through the open valve 13 into the filter. When the level of the pulp in the tank 31 has fallen sufficiently to lower the float 39, the compressed air is shut off, as already described, and the air in the tank is allowed to escape through the cock 36 and pulp flows into the tank as before. The pulp already in the filter is prevented from coming back by the check valve 34. The operation just described is repeated until the pulp in the filter has risen high enough to raise the float 18, at which time the valve 13 is closed by air admitted into one end of the cylinder 16 and the flow of pulp into the filter is shut off.

A reducing valve 44 is placed between the filter and the pipe 29 and maintains the pressure in the filter at a little below the pressure in the monte-jus, so that the pulp will flow gradually into the filter. A pipe 45 admits air through a reducing valve 46 into a box surrounding the hollow shaft 12 at the end of the filter, such air being under slightly greater pressure so that it will flow through certain passages in the shaft 12 and in reverse direc-

tion through the filter surfaces to distend the surfaces and facilitate cleaning thereof as described in my Patent No. 1,266,133, May 14, 1918.

It will thus be evident that I have provided a simple and efficient system for feeding pulp to pressure filters by which the pulp is gradually fed into the filter and a predetermined level of pulp maintained therein, the means for controlling the flow of pulp including emergency electrical means for shutting down the filter if the means for stopping the flow of pulp into the filter should become defective in any way as by a stick lodging in the valve 13 and preventing its closure.

In place of the check valves 34 and 35, air operated balanced valves may be used, operating from the float 39 in the same manner as the cock 36 is operated, and connected so that the opening of one valve causes closing of the other and vice versa. These balanced valves insure smooth operation and open and close regardless of pressure differences across the valves.

The use of an automatic monte-jus removes the necessity for a pressure pump and eliminates the cost of operating the pump and by maintaining the pressure in the monte-jus only slightly higher than that in the filter a gradual flow of sludge into the filter is assured instead of the rush of sludge under the pressure of a pump.

While I have described the system as applied to a pressure filter, it is evident that it may be equally advantageous in use with vacuum filters or under any conditions where a gradual controlled feed is required, and I do not, therefore, desire to limit the invention to the form of embodiment illustrated in the drawings, but to interpret the invention broadly within the scope of the appended claims.

I claim:

1. In combination with a continuous rotary pressure filter of the class described, automatic feed control mechanism comprising a monte-jus and means to operate it, a balanced valve, means in said filter to control said valve, an electrical circuit adapted to shut off said monte-jus operating means when said balanced valve reaches a predetermined position, and a connection between said monte-jus and said balanced valve to prevent fluctuations in pressure and pulp level in said filter.

2. In combination with a continuous rotary pressure filter of the class described, automatic feed control mechanism comprising a monte-jus, pressure means to operate said monte-jus, valve mechanism controlling the pressure in said monte-jus, valve mechanism in said filter adapted to limit the introduction of pulp in said filter, and electrical means to stop the introduction of pulp to said filter and the operation of said monte-jus.

when the pulp rises above a predetermined level.

3. In combination with a continuous rotary pressure filter of the class described, a monte-jus, said monte-jus and said filter being operated from the same pressure source, a balanced valve in said filter and a balanced valve in said monte-jus, said valves simultaneously operating to prevent changes of pressure or changes in level in the pulp in said filter.

4. In combination with a pressure filter of the class described, automatic feed control mechanism adapted to continuously supply said filter with filter pulp, said mechanism comprising a monte-jus, an inlet valve for said filter, a pilot valve, pulp level control means for operating said inlet valve operated by said pilot valve and pressure means for closing said inlet valve and for stopping said feed mechanism.

5. In combination with a continuous pressure filter of the class described, comprising a balanced inlet valve for the filter, a fluid pressure cylinder and piston for operating said valve, means to control said piston comprising a pilot valve and a float resting upon the liquid in said filter, said float through the rise and fall of said liquid actuating the pilot valve to cause the piston to open and close said balanced valve, and means actuated by the rising of said float above a predetermined level to stop the flow of liquid to said balanced valve.

35 6. In combination with a continuous rotary pressure filter of the class described, automatic feed control mechanism comprising a monte-jus, pressure means to operate said monte-jus, valve mechanism controlling the pressure in said monte-jus, valve mechanism in said filter adapted to limit the introduction of pulp in said filter, and means to stop the operation of said filter and monte-jus when the pulp rises above a predetermined level.

45 In testimony whereof I have affixed my signature to this specification.

JASPER A. McCASKELL.
